RECTIFIER

Samuel Ruben, New Rochelle, N. Y., assignor to
Sirian Lamp Company, Newark, N. J., a cor-
poration of Delaware

Application August 23, 1930, Serial No. 477,303

2 Claims. (Cl. 250—27.5)

This invention relates to rectifiers and particularly those of the gas filled type.

One of the objects of the invention is to provide a rectifier which will handle large current density.

Another object of the invention is to provide a rectifier which may be connected directly to the power line without intervening transformers.

Other objects and objects relating particularly to the construction and assembly of the various parts will be apparent as the description of the invention proceeds.

The invention is illustrated in the accompanying drawings in which:

Fig. 1 is a front elevational view of a half wave rectifier tube embodying the invention;

Fig. 2 is a plan view of the elements of the rectifier shown in Fig. 1;

Fig. 3 is a side elevational view of the elements shown in Fig. 1;

Fig. 4 is a circuit diagram showing the means of using the construction of Fig. 1;

Fig. 5 is a sectional front view of a full wave rectifier embodying the invention;

Fig. 6 is a plan view of the elements of Fig. 5;

Fig. 7 is a side view of the elements of Fig. 5;

Fig. 8 is a circuit diagram showing the connections which may be used with the construction of Fig. 5; and

Fig. 9 is an enlarged longitudinal sectional view of one end of one of the electron emitting elements.

Referring now more specifically to the drawings my improved rectifier has been shown as comprising an envelope 10 of glass or other transparent material mounted upon the usual press 11 which is made integral therewith and which supports the elements of the device. An electron emitting element 12 may be supported at its lower end upon a support rod 13 which may extend downwardly and may be sealed in the press 11 and at its upper end by a support rod 14 which may be bent backwardly and downwardly and inwardly again and may also be sealed in the press 11. The support rod 14 is, of course, spaced from the element 12 which may be positioned substantially on the axis of the envelope 10 if desired.

The element 12 may comprise a coil 15 (see Fig. 9) of resistance wire such as tungsten, tantalum, molybdenum, nichrome, or the like which may be wound in a coil of relatively small diameter. The outer surface of the coil may be coated with an electron emitting material 16 which may be any of the materials known in the art and used for that purpose, such as the oxides of the alkaline earth metals or mixtures of any of these ma-

terials. The materials may be spread on the surface of the coil in any desired manner as by brushing and then allowed to dry forming a hard coating on the surface of the coil.

A tubular anode or plate 17 may be positioned around the element 12 and may comprise a pair of cooperating semi-cylindrical members 18 having radial flanges 19 at the sides thereof which are adapted to be placed back to back to form a hollow cylinder with radial flanges extending diametrically opposite each other as indicated in Fig. 2. The flanges 19 may be provided at their edges with grooves 20 which fit the support rods 21 to which the flanges may be welded. The support rods 21 may extend downwardly and may be sealed into the press 11 while the upper ends thereof may be bent rearwardly and downwardly again and may be sealed in a bead 22 of glass or other suitable insulating material which may be supported upon the support rod 14 as clearly indicated in Fig. 3.

A leading-in wire 23 may be attached to one of the anode support rods 21 while leading-in wires 24 and 25 may be connected respectively to the support rods 13 and 14 for the element 12.

The envelope may be filled with an ionizable gas, preferably a monatomic gas, such as neon, argon, helium, krypton, or xenon, or mixtures of such gases, and to give best results I may prefer to have a pressure of about 200 mm. of mercury.

With the elements mounted on the press as indicated and the press sealed into the envelope the envelope may be connected in a manner well known in the art to an exhaust pump and an oven placed thereover to raise the temperature to between 350 to 400° C. or as high a temperature as the glass will stand without softening. A current may be run through the element 12 at this time sufficient to raise the temperature thereof to about 600° C. and this process may be continued until all of the gases and vapors are withdrawn from the envelope which is evidenced by the lack of fluorescence when high tension current from an induction coil is directed against the walls of the bulb. Current may then be increased through the filament to raise the temperature thereof to about 800° C. giving it a bright red color. This drives out the binder from the electron emitting material and other occluded gases which may be present. The gases thus driven off are withdrawn by the pump and when no more gas is found in the bulb the oven may be raised and the filament may be heated for a moment to approximately 1200° C. to drive out any more gases which may be present, the pump being connected all

this time to maintain a high vacuum which at this stage should be about .5 of a micron.

The pump may then be shut off and the filament current turned off and a small amount of 5 an inert gas, such as neon at about $\frac{1}{2}$ mm. pressure, may be admitted to the bulb and the filament current turned on again and gradually increased. Spots of localized discharge will then appear having a reddish color and will gradually increase and spread until a diffused bluish 10 glow completely fills the bulb. This process appears to activate the electron emitting coating and raise the efficiency thereof and usually takes less than ten minutes to complete. During this time 15 the current on the filament should not be raised too high so that the coating will not be destroyed or thrown off from the filament. If white discharge spots appear on the filament or support rods it is an indication that there are more gases 20 or vapors in the bulb and the bulb should again be exhausted and the process of activation repeated.

When the activation is completed the filament 25 temperature may be raised for a moment to about 1400° C. and then the vacuum pump again connected and the bulb pumped out to remove any 30 undesirable gases which may be thrown off during the activation process. The filament circuit may then be disconnected, the pump turned off, and about 50 mm. of neon gas followed by about 35 150 mm. of argon may be admitted to the bulb. The bulb may then be sealed off and may be ready for use after a small amount of magnesium is flashed to absorb any impurities.

In order to increase the conduction of the gas 40 in the envelope I may desire to add a small amount of metal vapor such as the vapors of mercury, caesium, or rubidium. If a small amount of a salt such as a chloride of one of these metals is placed in the container 26 for the 45 magnesium which may be supported on a wire 27 attached to one of the support rods, as the rod 21, the magnesium will react with the salt when it is flashed and liberate the free metal which will condense on the walls of the bulb to be evaporated when the rectifier becomes heated in use.

In Fig. 4 one circuit for using the device is 50 shown diagrammatically. The element 12 is connected to the secondary 28 of a transformer 29, the primary 30 of which may be connected to a source of alternating current. Another secondary winding 31 having one end connected to one end 55 of the winding 28 may have its other end connected through a load 32 to the anode 17.

When current flows in the primary 30 of the 60 transformer the element 12 is energized and an ionic discharge takes place along the surface of the element. This discharge appears like a halo around the element and is confined to the region 65 of the element by the pressure of the gas in the envelope. When the anode has a positive potential due to the direction of the current flowing in the secondary 31, current will flow between it and the element 12 through the ionic discharge field and when the anode is negative, when the 70 current is reversed in the secondary 31, the ionic discharge around the element 12 tends to collapse and no current will flow between these two. Thus current flows through the load circuit 32 only in 75 one direction, rectifying the current for $\frac{1}{2}$ of the cycle.

If a full wave rectifier is desired the construction shown in Figs. 5 to 8 inclusive may be used. Here an element 33 may be supported upon support rods 34 and 35, the latter connected to the

top of the element and being bent backwardly and downwardly where it may be sealed in the press 36. A pair of tubular anodes 37 and 38 both having relatively the same diameter may be positioned around the element 33 concentrically therewith and spaced apart longitudinally as indicated in Fig. 5. The anode 37 may be formed of a single strip of nickel or other metal bent to form a hollow cylinder provided with a flange 39 which may be welded to a support rod 40 sealed 10 in the press 36 and extending upwardly spaced from the element 33 and bent rearwardly above the flange 39 and downwardly again where it may be sealed in a bead 41 attached to the support rod 35. The lower anode 38 may be formed similarly to the anode 37 and provided with a flange 42 which may extend in the opposite direction to the flange 39 and which may be welded to a support rod 43. The rod 43 may extend upwardly beyond the anode 38 and may be bent rearwardly and downwardly where it may be sealed into the bead 41 similarly to the support rod 40. In this case the element 33 may be formed similarly to the element 12 as described. 15

In Fig. 8 a circuit is shown in which the full 20 wave rectifier may be used. The element 33 may be connected across the ends of a secondary 48 of a transformer 49, the primary 50 of which may be connected across an alternating current source. The anodes 37 and 38 may be connected 25 to the ends of another secondary winding 51 and a center tap 52 on the winding 51 may be connected through the load circuit 53 to a center tap 54 on the secondary winding 58.

Alternating current through the primary 50 of 30 the transformer 49 energizes the secondary 48 and therefore the element 33 which is caused to emit electrons and a halo of ionic discharge forms along the element. During one cycle the anode 37 becomes positive and the anode 38 negative 35 due to the current flowing in the secondary 51 and during the other cycle this condition is reversed. When the anode 39 is positive current flows between it and the element 33 while the negative anode 38 tends to collapse the halo 40 around that part of the element. When the anode 38 becomes positive and the other negative 45 the condition is reversed so that during both cycles of the alternating current wave unidirectional current will flow through the load circuit 53. It will thus be seen that the device 50 shown in Figs. 5 to 8 inclusive will rectify both sides of the alternating current wave.

While a single element is shown in both constructions it is evident that the number of elements may be increased depending on the resistance thereof and the desired voltage and the elements may have any desired construction as for instance a single straight wire may be used although I prefer to use a coil so as to increase 60 the potential drop per unit length of the coil.

Many modifications of the invention may be resorted to without departing from the spirit thereof, and I do not therefore desire to limit myself to what has been shown and described 65 except as such limitations occur in the appended claims.

What I desire to claim is:

1. In a rectifier for alternating current in a load-containing circuit a resistance wire, a 70 coating of electron emitting material upon the surface of said wire containing alkaline earth metal oxides, an electrode positioned in the vicinity of said wire, and an ionizable gas having a pressure of substantially 200 mm. of 75

mercury surrounding said element and electrode, the breakdown potential of said gas when ionized by the emission of electrons from the coating of electron material arising from the passage of a current through the resistance wire being less per unit length along said wire than the unit potential necessary to bring said wire and coating to electron emitting temperature.

5. 2. In a rectifier for alternating current in a

load-containing circuit, a coil of resistance wire, a coating of electron emitting material upon the surface of said coil, an electrode positioned in the vicinity of said coil, and a mixture of neon and argon gas surrounding said coil and electrode and having a pressure of substantially 200 mm. of mercury.
